United States Patent

Des. 242,529
Patented Nov. 30, 1976

242,529

LABORATORY TEST PACK

Bill E. Albright, Diamond Bar, Calif., and Michael D'Aquino, Miami, Fla., assignors to American Hospital Supply Corporation

Filed Apr. 10, 1975, Ser. No. 566,924

Term of patent 14 years

Int. Cl. D9—03

U.S. Cl. D9—192

FIG. 4

FIG. 5

FIG. 6

FIG. 1 is a front elevational view of a laboratory test pack showing our new design;

FIG. 2 is an elevational view looking from the left of FIG. 1;

FIG. 3 is an elevational view looking from the right of FIG. 1;

FIG. 4 is a top plan view;

FIG. 5 is a bottom plan view; and

FIG. 6 is a rear elevational view thereof.

We claim:

The ornamental design for a laboratory test pack, substantially as shown.
